UNITED STATES PATENT OFFICE.

DARIOUS SWAN, OF WORTHINGTON, INDIANA.

SPARK PLUG.

1,412,320.

Specification of Letters Patent. Patented Apr. 11, 1922.

Application filed February 26, 1920. Serial No. 361,534.

To all whom it may concern:

Be it known that I, DARIOUS SWAN, a citizen of the United States, residing at Worthington, in the county of Greene and State of Indiana, have invented a new and useful Spark Plug, of which the following is a specification.

This invention relates to new and useful improvements in spark plug constructions employed in the ignition systems of internal combustion engines, and it is the primary object of the invention to provide a plug having visible electrodes adapted to spark simultaneously with the sparking of the usual spark points, thus indicating the operativeness of the plug.

A further object of the invention is to provide means to intensify the electric current passing through the plug, by interrupting the current through the main electrode.

A still further object of the invention is to provide a plug of this character having an intensifying spark point cooperating with the usual spark points of the plug, to further intensify the electrical current thereby producing an exceedingly hot spark.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 illustrates a side elevational view of a spark plug constructed in accordance with the present invention.

Figure 2 illustrates a longitudinal sectional view taken on line 2—2 of Figure 1, and

Figure 3 illustrates a bottom plan view of the plug.

Referring to the drawing in detail, the invention is shown as including a shell comprising a lower section 5 and an upper section 6, the lower section 5 being threaded as at 7 to permit the plug to be inserted in the usual spark plug opening of the engine cylinder, to which the plug is applied.

The upper section 6 is also threaded and cooperates with the threads 8 formed on the upper extremity of the lower section 5, for securing the upper section and lower sec-

tion together, the upper section being provided with a flange 9 adapted to cooperate with the core 10 of the plug proper, for securing the core within the shell.

Embedded within the core 10, which is formed of porcelain or other suitable insulating material, is a main electrode 11 which has its upper end terminating short of the upper end of the core 10, and in spaced relation with the lower end of the relatively short electrode 12 to provide a spark gap between the electrodes 11 and 12 to intensify the current passing through the plug.

The lower end of the electrode 11 extends below the lower end of the core 10 to provide the spark point 13, which extends towards the point 14 disposed between the points 13 and 15, the point 15 being provided on the lower extremity of the electrode 16, forming an important feature of the present invention. From the foregoing it is obvious that when current is applied to the electrode 12, the same on passing to the electrode 11 jumps the space between the electrode 11 and 12, to the end that the current is intensified. As the current passes to the lower extremity of the plug proper, the current jumps between the points 13, 14 and 15 with the result that the current is further intensified and an exceedingly hot spark is produced.

Formed within the core 10, and disposed adjacent the upper extremity thereof is a chamber 17 which accommodates the upper end of the electrode 16 cooperating with the conductor 18, which is in the form of a relatively long arm having its lower extremity contacting with the inner wall of the upper section 6 of the shell, to ground the current through the shell, the intermediate portion of the arm being apertured to support the disk 19 formed of mica, or other suitable transparent material, and as shown this disk 19 is clamped between one wall of the arm, and the downwardly extending conductor 18.

The usual insulating cap 20 is positioned on the upper extremity of the core 10, and cooperates with the thumb screw 21 for securing a circuit terminal to the plug, the screw 21 being constructed to operate on the upper extremity of the electrode 12.

In the operation of the device, it is obvious that when current is supplied to the plug through the electrodes 11 and 12, the current will pass between the points 13, 14 and 15,

through the electrode 16, where the current will jump from the upper end of the electrode 16 to the conductor 18, producing a spark at this point simultaneously with the 5 sparking at the sparking end of the plug. From the foregoing it is obvious that if a spark is produced between the upper end of the conductor 18 and electrode 16, a spark is being produced between the points 13, 14 and 10 15, but if no spark is visible through the disk 19, the indications are that no spark is being produced between the points 13, 14 and 15 to the end that the plug should be removed and cleaned, or repaired.

15 Having thus described the invention, what I claim as new is:—

In a spark plug, a shell, a core positioned

within the shell, said core having a chamber formed adjacent to the upper end thereof, a conductor having portions thereof bent 20 to grip a disk of transparent material, to provide a cover for the chamber, one end of the conductor contacting with the shell, a central electrode, and an electrode having one end disposed in the chamber and positioned in proximity to the conductor.

In testimony that I claim the foregoing as my own, I have hereto affixed my signature in the presence of two witnesses.

DARIOUS SWAN.
